UNITED STATES PATENT OFFICE.

WILLIAM E. MOREY, OF CHICAGO, ILLINOIS, ASSIGNEE TO NATIONAL DUMP CAR COMPANY, A CORPORATION OF MAINE.

DOOR-ACTUATING MECHANISM FOR GENERAL-SERVICE CARS.

1,175,165.

Specification of Letters Patent. Patented Mar. 14, 1916.

Application filed March 13, 1914. Serial No. 824,509.

To all whom it may concern:

Be it known that I, WILLIAM E. MOREY, a citizen of the United States, residing at Chicago, in the county of Cook and State of Illinois, have invented certain new and useful Improvements in Door-Actuating Mechanism for General-Service Cars, of which the following is a specification.

My invention relates in general to freight cars, and more particularly to door actuating mechanism for freight cars of the type known as "general service" cars.

The practicability of general service cars depends largely upon the efficiency of the mechanism for operating the drop doors which form the principal part of the car floor. It is desirable that the operating mechanism should tightly close the doors to prevent leakage of the lading; should securely support the doors in closed position so as to avoid accidental dumping of the lading; and should permit the dropping of the doors to discharge the lading. It is further desirable that the door operating mechanism should be strong and durable in construction and at the same time simple in operation.

The primary object of my invention is to provide a freight car of the type having drop floor doors actuated by chains connected with rotary shafts, in which the weight of the doors when closed and of the load on them will not be imposed upon the chains, but will be sustained by automatically actuated supports which transmit the load on the doors to the car frame.

A further object of my invention is to provide a freight car of the character referred to in which the operation of the rotary shafts in closing the doors will permit the automatic actuation of supporting devices to engage and sustain the doors when closed independently of the rotary shafts and the chains connected thereto, and in which the rotary shafts will disengage such devices from the doors to permit them to drop to open positions.

A still further object of my invention is to provide door operating and supporting mechanism for the drop doors of freight cars which will be simple in construction, convenient in operation, and efficient in use.

My invention will be more fully disclosed hereinafter with reference to the accompanying drawings in which the same is em-

bodied in a convenient and practical form, and in which—

Figure 1 is a side elevational view of a portion of one end of a freight car equipped with my invention, parts being broken away; Fig. 2 an enlarged detail sectional view of one end of one of the transverse members of the underframe and parts of the door operating mechanism adjacent thereto; Fig. 3 a sectional view on the line 3, 3, Fig. 2; Fig. 4 an enlarged cross sectional view showing a door in open position; Fig. 5 a detail sectional view showing the door in partially raised position before the engagement therewith of the supporting devices. Fig. 6 a view similar to Fig. 5 showing the door completely closed. Fig. 7 a view similar to Fig. 6 showing a slightly modified form of door supporting device; and Fig. 8 an elevational view of one of the supporting devices.

Similar reference characters are used to designate similar parts in the several figures of the drawings.

Reference letter A indicates the center sill, which may be of any suitable construction, such, for instance, as of the "box girder" type.

B indicates the end sill of the car, B' one of the bolsters, and C one of the cross bearers or transverse members of the underframe.

D designates one of the end walls of the car, and E one of the side walls.

F indicates one of the drop doors which is pivotally supported by hinges G upon the center sill. The door F is adapted to be swung upwardly about its inner edge into a closed position flush with the plane of the floor of the car, or to be swung downwardly, to the position shown in Fig. 4.

H designates one of the side stakes which depends below the floor level and is riveted to the adjacent end of the bolster, or to the adjacent end of one of the transverse members C, as well as to a reinforcing flanged plate C' secured to the end of the transverse member.

J indicates a rotary shaft extending longitudinally of the car and journaled in the ends of the transverse members of the underframe. The end of the shaft J projects through the end sill B and is there provided with suitable pawl and ratchet mechanism j for rotating the shaft and holding it in positions to which it may be rotated. Four of

such shafts are usually provided, two on each side of the car, extending from the opposite ends of the car to the transverse center thereof. Pairs of chains I connect the shafts J with the swinging edges of the adjacent drop doors F, any suitable means being provided for connecting the chains with the drop doors adjacent their opposite sides, such for instance as eye-bolts i adjustably secured to brackets F' fixed to the under surfaces of the doors.

A car of the construction above described is one well-known and does not in itself embody my invention, but is merely illustrated and described in order that the construction and operation of my improved door actuating mechanism may be fully disclosed. It will be obvious that my invention may be applied to cars of other specific constructions than that above described.

A bearing plate K is secured to the vertical web of each of the transverse members C at each end thereof, such plates being within the laterally projecting marginal flange c around the web of the transverse member. Each bearing plate K is provided with a cylindrical portion k which projects through an opening in the web of the transverse member to which it is secured. Rotatably supported within each of the cylindrical portions k of the bearing plate K are the adjacent ends of sleeves L', L² through which the shaft J extends. The cross section of shaft J is preferably angular and the openings through the sleeves correspond in cross section so that the sleeves are non-rotatably mounted upon the shaft. In order to prevent longitudinal movement of the sleeves upon the shaft suitable fastening devices, such for instance as bolts l, are provided.

Rigidly secured on the ends of the sleeves L', L², adjacent the opposite sides of the cylindrical bearing k, are eccentrics l', l², such eccentrics being preferably formed integrally with the sleeves upon which they are mounted. Rigidly secured to each end of each of the transverse members of the car frame is a bracket M comprising front and side flanges which surround the adjacent end of the transverse underframe member, and also surround the adjoining portion of the reinforcing bracket C'. Each bracket M is provided with a lower wall which underlies and is rigidly secured to the lower flanges of the transverse member of the underframe and the adjacent reinforcing bracket. The brackets M are rigidly secured to the car frame, and preferably also to the lower ends of the car stakes H, as shown in Figs. 1 to 7. A bolt or rod m extends through the side walls of each bracket M and serves as a fulcrum for the lower ends of the oscillating supporting devices N' and N². Each of the supporting devices

or latches N', N² is provided with an elongated opening N through which the shaft J passes, and which permits the free oscillation of the latches relatively to the shaft. Each of the latches N', N² is also provided with a lug n which overlies the adjacent eccentric l' or l² and is engaged by such eccentric to oscillate the supporting device. Each of the supporting devices N', N² is also provided with a projection n' extending toward the edge of the adjacent door and adapted to oscillate into the path of such door after it has been closed.

In order to insure the oscillation of each of the supporting devices N', N², beneath the edge of the adjacent door after it has been closed, a tripping device O is provided which may be conveniently fulcrumed on a bracket o secured to the inwardly inclined plate e forming the lower portion of the side wall of the car. The tripping devices O align with the supporting devices and are provided with ends o² which overlie shoulders n² on the supporting devices. Each tripping device O depends at its opposite end into the path of the upper surface of the door so as to be oscillated through engagement with the door when the latter is completely closed. In lieu of the tripping device O other means may be provided for insuring the oscillation of the supporting devices into door supporting positions, such for instance as a spring S interposed between each door supporting device and the underlying lateral flange on the adjacent transverse car frame member, as shown in Fig. 7. The ends of the spring engage studs s' and s², the latter being on the supporting device and the former on the flange of the transverse underframe member.

The operation of my improved door actuating mechanism is as follows: When the doors are in the open position shown in Fig. 4 and it is desired to close them, the shaft J is rotated in a direction to wind thereon the chains I and thereby swing the outer edges of the doors upwardly. When the doors reach the elevated position shown in Fig. 5 their outer edges engage the adjacent cam surfaces of the supporting devices and oscillate such devices away from the doors. When the doors are completely closed, as shown in Fig. 6, the supporting devices oscillate by gravity into position for the projections n' thereon to underlie the longitudinal reinforcing strip f beneath the edge of the door, as shown in Fig. 6. The oscillation of the supporting devices into their door supporting positions is insured by means of the tripping devices O, the inner ends o' of which are engaged by the upper surfaces of the doors as they are closed, so that such devices are oscillated and their outer ends o² through engagement with the projections n² on the supporting devices

positively oscillate such devices into door supporting position with their projections n' beneath the doors so as to support them independently of the rotary shaft and chains.

5 The springs S shown in modification illustrated in Fig. 7 operate to positively oscillate the supporting devices to project the cams n' thereon beneath the doors after the doors have been lifted into closed position.

10 When it is desired to lower the doors the shaft J is rotated in a direction to permit the chains to unwind. The initial rotation of the shaft J in a direction to unwind the chains causes the portions of the eccentrics l' and l^2 having the greater radius to engage the overlying lugs n on the supporting devices N' and N^2 , and to thereby oscillate such devices outwardly so as to remove the cam projections n' thereon from beneath the outer edges of the doors, thereby permitting the doors to drop by gravity. In Fig. 7 the latch is shown in the position to which it has been oscillated by the cam against the tension of the spring S so that the door is 25 free to drop. The relation of the eccentrics l' and l^2 to the shaft J is such that in raising the doors the shorter radius of the eccentrics is opposite the lugs n on the supporting devices at the time the doors are approaching closed position. The extent of the surface of shorter radius of the eccentric is such as to permit a sufficient latitude in the rotation of the shaft to compensate for any stretching in the chains, so that the 35 doors will be completely closed before the portions of the eccentrics of greatest radius engage the lugs on the supporting devices. Should, however, the portion of the door to which each chain is connected be not completely closed, it will still be supported inasmuch as the projection n' on each locking device will swing beneath the outer edge of the door before the door has been completely closed. The position of the door supporting 40 devices relatively to the doors and to their pivotal connection with the car frame is such that the weight transmitted by the doors to such devices does not tend to disengage the supporting devices from the 45 doors, but on the other hand a tendency of the weight of the doors to swing the supporting devices about their points of pivotal support serves to more tightly retain the doors in closed position.

50 From the foregoing description it will be observed that I have invented an improved door actuating mechanism for freight cars by means of which the drop doors are firmly supported in closed position independently 55 of the door raising and lowering mechanism, thereby relieving such mechanism of the load supporting strains, such strains being transmitted directly to the car frame through supporting devices automatically actuated by the door raising and lowering

mechanism in its normal operation in raising and lowering the doors.

While I have described my invention with more or less minuteness and as being embodied in certain precise forms, yet it will be understood that I do not desire to limit myself thereto unduly, or any more than is pointed out in the claims. On the contrary, I contemplate all proper changes in form, construction, and arrangement, the omission of immaterial parts, and the substitution of equivalents, as circumstances may suggest or necessity render expedient.

I claim:

1. In a freight car, the combination with a downwardly swinging door, of a rotary shaft, chains connecting said shaft with the swinging edge of said door to close the same, a movable door supporting device mounted upon the car frame and adapted to automatically engage and support said door when closed, said device having an opening through which said shaft extends for permitting the movement of said device relatively to said shaft, and means for moving said device relatively to said shaft out of door supporting position actuated by the initial rotation of said shaft in a direction to unwind the chains.

2. In a freight car, the combination with a downwardly swinging door, of a rotary shaft, chains connecting said shaft with the swinging edge of said door to close the same, a movable door supporting device mounted upon the car frame and adapted to automatically engage and support said door when closed, said device having an opening through which said shaft extends for permitting the movement of said device relatively to said shaft, an eccentric fixed to said shaft, and a projection on said device extending into the path of said eccentric and engaged thereby to move said device out of door supporting position during the initial rotation of said shaft in a direction to unwind the chains.

3. In a freight car, the combination with a downwardly swinging door of a rotary shaft, chains connecting said shaft with the swinging edge of the door to close the same, an oscillatory door-supporting device upon the car frame, and means for automatically operating said device into positions to support the door when closed, said means being actuatable by the closing movement of the door and comprising a pivoted member.

4. In a freight car, the combination with a downwardly swinging door, of a rotary shaft, chains connecting said shaft with the swinging edge of the door to close the same, an oscillatory door-supporting member mounted upon the car frame, said member being provided with a shoulder, and means for automatically oscillating said device into position to support the door when closed,

said means comprising a pivotally mounted dog having a portion arranged to coact with the shoulder of said first-named member and a second portion projecting into the path of movement of the door in such wise that the latter in its closing movement will actuate said supporting member.

In testimony whereof, I have subscribed my name.

WILLIAM E. MOREY.
